UNITED STATES PATENT OFFICE.

WILLIAM C. RE AND BERNARDO RASO, OF NEW YORK, N. Y.

SINGLE-SOLE SHOE.

Application filed December 5, 1924. Serial No. 754,185.

This invention relates to improvements in the construction of shoes, and proposes a cheapening and simplification in the manufacture of such articles.

One of the features of this invention is to provide a shoe construction in which a single piece of leather is caused to serve both as insole and outsole.

A further object of the invention is the provision of a sole construction for shoes, in which the counter leather is retained between the two portions of a split sole.

Another object of the invention is the provision of a shoe in which the upper and sole may each be formed of a single piece of material and may be joined by a single stitch passing around the welt in the preliminary assembling of the shoe.

With these and other objects in view, as will appear hereafter, we have shown one form of execution of our improved shoe in the accompanying drawing, in which—

Figure 1 is a perspective view showing a partly assembled shoe;

Fig. 2 is a cross section through the toe portion of the shoe;

Fig. 3 shows a longitudinal section of the shoe, and

Figures 4 and 5 are similar sections with modified heels.

The sole 1 is composed of a single piece of leather which is split around the welt edge, and a portion of the upper surface removed to leave a shoulder as shown at 2. At the rear, the sole is split from the heel forward to the instep, thus forming the two portions 3 and 4. The upper 5 in the example shown, is composed of a single piece of material, either single ply or having a reversed inner lining layer. It may be drawn over the last after having been shaped into an appropriate form and joined at the rear by a stitching 6. The counter portion 7 of the upper is turned under the upper section 3 of the sole and tacked in place as shown at 8, with a possible interposition of packing 9 to give the proper form to the inside of the shoe. At the front, the upper is turned outwardly as shown at 10 to conform to the reentrant angle of the shoulder 2. During the first operations of assembly, the upper may be held in this position by tacks or staples 11, although this is not necessary for the construction of the shoe. After the upper has been positioned upon the shoulder formed in the sole, a narrow welt strip 13 is placed over the upper, and the

whole stitched down as shown at 14. This single operation serves to hold the upper and sole in their final relation.

The welt strip 13 is continued at each end beyond the ends of the out-turned flange 10 of the upper, as shown at 13a, so that the end stitches 14a are relieved from strain.

The heel 16 may be of any appropriate design as shown in Figures 3, 4 and 5. In Fig. 3 is shown a heel construction in which the heel wedge 17 is inserted between the two sections 3 and 4 of the sole, and the several elements are tacked together as shown at 29. In Fig. 4, we have shown a Cuban heel, in which the two sections 3 and 4 of the sole have been connected together, and the heel 16 inserted entirely below the lower section of the sole. In Fig. 5 we have shown a French heel, which is mounted entirely upon the upper section of the split sole, and the lower section 4 has been cut away at the instep end of the heel 16. By proper conformation of sole and upper, the heel block 16 of Fig. 3 may be omitted and a baby-sole shoe produced.

In finishing the shoe, the trimming welt strip 24 is placed over the seam shown at 14, and is cemented in place and rolled down to form a knurled edge if desired.

To support the instep of the shoe, it is provided with a steel spring member 26 which is inserted at its forward end into a gash 28 formed in the shank portion of the sole, and at its rear end is tacked as at 29 to the heel portion of the sole. It is obvious that this spring will support the instep of the shoe and the foot of the wearer. To prevent contact of this spring with the stocking of the wearer, we prefer to insert a cover pad 30 of soft leather, which may be fastened in place by adhesive in the usual manner.

It is obvious that minor changes may be made in the details of construction and the arrangement of the parts without departing from the spirit of the invention as set forth in the appended claims.

Having thus described the invention, what we claim as new and desire to secure by Letters-Patent, is—

1. A shoe having a one-piece sole with a split heel portion and a channeled portion along the toe and instep periphery, a one-piece upper having its lower edge divided by gashes at each side, the instep and toe portion of said upper being outturned and seated on said channeled portion of said sole, the heel or counter portion of said upper being

5 inturned between the parts of said split heel, a separate welting strip seated on said instep and toe portion of the upper and projecting therebeyond at the rear ends to overlie the lower part of said split heel, and a single stitching to unite said welting strip, said outturned portion of the upper, said channeled portion, and said lower heel portion.

2. A shoe having an integral sole with a split heel portion, an upper outwardly lasted at the front and inwardly lasted at the counter between the portions of the split sole, a welting strip located over the outwardly

lasted portion of the upper and extending at each end beyond such outwardly lasted portion, and a stitching uniting said sole, upper and welting and joining the extended ends of the welting strip directly to said sole, whereby to strengthen the attachment of the upper to said sole at the line of junction of the inwardly and outwardly lasted portions of the upper. 15 20

In testimony whereof, we affix our signatures

WILLIAM C. RE.
BERNARDO RASO.
